UNITED STATES PATENT OFFICE.

ELIJAH McCOY, OF DETROIT, MICHIGAN, ASSIGNOR TO YPSILANTI LUBRICATOR COMPANY,
OF YPSILANTI, MICHIGAN, A CORPORATION OF MICHIGAN.

LUBRICATOR.

No. 903,306.

Specification of Letters Patent.

Patented Nov. 10, 1908.

Application filed March 11, 1903. Serial No. 147,341.

To all whom it may concern:

Be it known that I, ELIJAH McCoy, residing at Detroit, in the county of Wayne and State of Michigan, a citizen of the United States, have invented certain new and useful Improvements in Lubricators, of which the following is a specification, reference being had therein to the accompanying drawings.

- 10 The invention relates to improvements in lubricators, and is more particularly designed for use in connection with engines or locomotives operating under high steam pressure.
- 15 The invention has more special reference to a construction of lubricator in which the lubricant is positively fed to the cylinder or other bearing to be lubricated against high pressure, and it is the special object of 20 the present construction to provide means for controlling the feeding of oil so as to secure uniformity of action under varying conditions.

Heretofore lubricators have been constructed in which the lubricant is fed to the cylinder by the action of a positive plunger pump. Regulators have also been provided for partially controlling the feeding of the oil from said pump under varying back 30 pressures from the engine cylinder. Experience has demonstrated however that to secure a uniform feeding of the oil under all conditions is a very difficult problem. Thus, at times the oil is more fluid than at other 35 times, due to differences in temperature, and as a consequence the feed is varied. Again, where the oil is fed by gravity to the force pump or is drawn therein by the suction of said pump, the feed will be varied according to the height of the oil in the tank. Again, under certain conditions the back 40 pressure from the cylinder will rise to a higher point than even the full boiler pressure, which will result in the variation of the oil feed.

In the present invention it is an object to secure a sight oil feed which may be adjusted according to the requirements of the work and will not be changed by the variable conditions above referred to.

To this end the invention consists first in the peculiar construction of a regulator for governing the feed of the oil in the tallow pipe. Further in the peculiar construction 55 and combination with a positive force feed

for the lubricant, of an adjustable sight feed and regulator for securing uniformity of action in all adjustments. Further in the peculiar construction of a heater for retaining the oil at uniform temperature when fed 60 from the tank, and further in the peculiar construction, arrangement and combination of parts as hereinafter described and claimed.

In the drawings Figure 1 is a diagram illustrating the various parts and connections comprising my improved lubricator. Fig. 2 is a perspective view of the lubricator as arranged in connection with a locomotive boiler. Fig. 3 is a section through the governor for the tallow pipe. Fig. 4 is a horizontal section through the oil tank showing the construction and arrangement of a heater therefor. Fig. 5 is a vertical section substantially on line $x-x$ Fig. 4.

Generally described, my improved lubricator comprises a steam operated force pump A, an oil tank B, a sight feed C intermediate said tank and pump, a governor D controlling the feeding of the pump into the tallow pipes, and governing devices for controlling 70 the uniform feeding of the oil in the sight feed, as will be hereinafter set forth.

For propelling the oil through the sight feed, I preferably employ a hydrostatic feed comprising a condenser E having a steam 85 connection F with the boiler, and a conduit G for the condensation extending to the bottom of the oil tank.

H is the oil discharge pipe which extends from the top of the chamber within the tank 90 downward and outward through the fitting I which forms the base of the sight feed. This sight feed is provided with the usual transparent tube a which is filled with water, and the oil nozzle b at the base thereof 95 controlled by the valve c. The upper end of the tube a is connected in the fitting J which forms the connection to the conduit K leading to the suction chamber of the pump, and also has preferably formed there- 100 in the connections for the heater.

The heater consists of a radiator L extending into and across the tank near the upper end thereof. This radiator may be formed integral with or connected to the fitting J, and connected with the tank by a screw threaded engagement as indicated at d. The inner end of the radiator is closed by a plug e and its outer end communicates with a channel f formed in the fitting J and 110

passing around the chamber *g* connecting with the tube *a*. One end of the channel *f* connects with a steam conduit *M*, the passage of the steam being controlled by a valve *N*. As shown this valve is arranged in the end of the fitting *J* and is in the form of a needle valve. The opposite end of the channel *f* is connected by a restricted port *h* with the passage *i* leading from the chamber *g* and connecting with the conduit *K*. The arrangement just described is such that the flow of steam from the conduit *M* to the radiator *L* is governed by the valve *N* and the condensation of the steam is discharged through the restricted ports *h* into the passage *i* where it is free to flow back into the tube *a* to replenish the water in the sight feed.

Intermediate the fitting *J* and the conduit *K* is arranged a governor for regulating the flow of oil which is of the following construction: *H'* is a casing in which is formed the diaphragm *m*, having formed therethrough the ports *o* and *p*. The port *o* is adapted to be closed by a valve *O* which is in the nature of a check valve, and is slidably secured in the cylindrical casing *q*. This casing is connected to a steam conduit *P* leading from a source of steam at boiler pressure, and admitting said steam into the casing *q* so as to bear upon the end of the valve *O*. With the arrangement just described the valve *O* is normally held to its seat by steam pressure and can only be opened where the pressure in the chamber *i* and acting upon the lower end of the valve *O* is in excess of the pressure acting upon the upper end of the said valve, as will be hereinafter set forth.

The valve *O* is provided with a channel *r* therein which is sufficient to permit the condensation accumulating in the casing *q* above the valve to drain into the casing *k*. Whenever the valve *O* is opened it will pass through the ports *o* and will flow back into the tube *a*, thus the water in the sight feed may be replenished from this source as well as from the heater *L*, so that even when the heater is out of operation as in warm weather, there will be no lack of water in the sight feed.

The oil passing through the conduit *K* is fed into the pump *A*, which latter may be of any suitable construction, and as it forms no part of the subject matter of the present invention the detail construction is not shown. From the pump *A* the oil is forced through the conduits *Q* and *Q'* which connect with the tallow pipes *R* *R'*, and intermediate each of these conduits and its tallow pipe is arranged the regulator *D*.

As has been previously stated, under certain conditions the back pressure from the engine may equal or even exceed that of the boiler, while at other times a suction is pro-

duced which will reduce the pressure to below atmosphere. To secure uniform feeding of the oil under these varying conditions, the regulator *D* is preferably formed of the following construction: *s* is the casing containing the diaphragm *t* which has the port *u* therein. *v* is a valve seated on the diaphragm *t* so as to close the port *u*. A portion of the body of this valve is preferably of uniform diameter, and is slidably secured in a cylindrical portion *w* of the casing. The outer end *x* of the valve is however of larger diameter, and is cup shaped, as shown at *y*. This portion is also slidably arranged in a cylinder *z* forming a part of the casing. *S* is a steam conduit connecting with the cylinder *z*, and leading from a source of steam at the boiler pressure. Thus the area exposed to pressure at the upper end of the valve is in excess of the area acted upon by the oil when propelled by the pump, and consequently the valve can only be opened where the pressure in the oil conduit is considerably in excess of boiler pressure.

The parts being constructed as shown and described, the operation is as follows: The pump *A* when in operation is adapted to deliver oil at a pressure considerably greater than the pressure in the boiler, and sufficient to overcome the resistance of the valve *v*. At the same time the resistance of said valve being constant it will prevent the action of the pump from varying with variations of pressure in the tallow pipe due to the difference in back pressure from the engine. The valve will also always be forced to its seat at the end of each stroke of the pump, even where the back pressure in the tallow pipe is in excess of the boiler pressure. This would not be the case if the area of the upper end of the valve were only equal to that of the lower end, for the reason that then the valve when once opened would be subjected to the pressure developed within the tallow pipe, and if this were greater than boiler pressure the valve would remain open. With my improved construction pressure on the upper end of the valve is sufficient to close it under the highest back pressure that is ever developed in the tallow pipe.

By making the upper end of the valve cup-shaped any sediment which may collect with the condensation in the pipe *S* will be lodged in the cup and will not find its way between the valve and its bearing in the cylinder, thus the danger which might otherwise occur of the valve becoming fast is avoided.

The regulator *D* is adapted to regulate the action of the pump *A* so as to secure a uniform propelling of the oil by said pump. It does not however in any way govern the operation of the sight feed, and as a consequence the amount of oil actually delivered by the pump may be varied according to the

adjustment of the feed. The amount of oil delivered from the tank L is primarily determined by the adjustment of the valve c which regulates the passage leading to the nozzle b. This valve alone would however be inadequate to the securing of an absolutely uniform feed, were it not for the other devices provided. One essential to the uniform feeding of the oil is that it should be delivered to the nozzle b under constant pressure. This is accomplished by means of the hydrostatic feed in which the pressure acting upon the oil is always equal to boiler pressure plus the weight of the hydrostatic column in the condenser E. Another essential is that the suction from the pump be uniform.

It is obvious that where the amount of oil fed to the pump is less than the capacity of the pump that the latter will produce a varying suction in the conduit K and this would cause a varying feed through the nozzle b. To prevent such an action the port p through the diaphragm m is sufficiently restricted so as to be capable of feeding only a minimum amount of oil to the conduit K, and where a greater quantity is passed through the sight feed it will be compelled to pass through the port o by lifting the valve O. As however the valve O is constantly acted upon by the pressure of steam in the conduit P it will be returned to its seat as soon as the oil is delivered through the port o or it will be held in a position to restrict said port according to the amount of oil passed therethrough.

Another essential condition to the uniform feeding of the oil is that it be approximately of the same temperature. This may be accomplished by means of the heater L and the valve N governing the same, thus in cold weather the valve N may be opened to admit sufficient steam into the radiator so as to raise the temperature of the oil therein, and when the valve is once set in the proper position it will maintain the oil at the required temperature until a change of condition requires another adjustment. In this connection it may be said that the condensation from the heater L being discharged into the chamber i in which there is a constant pressure, the amount of heat radiated will be maintained uniform.

Another essential condition to the uniform feeding of the oil is the presence of a fluid in the pipe K which will uniformly carry the oil to the suction of the pump. Inasmuch as the quantity of oil fed by the lubricator is varied from time to time, it is obvious that at times the amount fed will occupy but a small part of the capacity of the conduit. If there were no other medium in the conduit, the suction of the pump would have no effect in the feeding of the oil which would either accumulate in the conduit or be

fed by gravity. Should an accumulation occur then the oil passing directly from the sight feed would be held in the conduit for a considerable time before finally entering the pump.

With my construction the accumulation of oil in the conduit is avoided by the introduction of steam through the restricted ports. The steam so admitted acts as an expansible medium in the conduit K which at each suction of the pump propels the oil forward in the conduit so that it is uniformly delivered to the pump.

What I claim as my invention is:

1. In a lubricator, the combination with a force pump for positively propelling the oil, of a hydrostatic feed comprising an oil tank and steam condenser for delivering the oil to said pump.

2. In a lubricator, the combination with a force pump for positively propelling the oil, of an oil tank, a conduit through which the oil from said tank is delivered to the suction of said pump, and means for introducing into said conduit, a fluid medium at greater than atmospheric pressure forming a vehicle for conveying the oil uniformly to said pump.

3. In a lubricator, the combination with a force pump for positively propelling the oil, of an oil tank, a conduit connecting said tank with the suction of said pump, a check in said conduit, and means for introducing into said conduit on the pump side of said check a fluid medium at greater than atmospheric pressure constituting a vehicle for conveying the oil uniformly to the pump.

4. In a lubricator, the combination with a force pump for positively propelling the oil, of an oil tank, a conduit connecting said tank with the suction of said pump, a partition in said conduit having a restricted port therethrough and another port of greater area, a check valve normally closing the larger port, a hydrostatic feed for delivering the oil from said tank and having a condenser subjected to steam pressure, means for subjecting said check valve to a relatively equal steam pressure whereby the differential pressure acting upon said valve is equal to that developed by the hydrostatic column, and means for introducing into said conduit beyond said valve fluid medium constituting a vehicle for conveying the oil uniformly to said pump.

5. In a lubricator, the combination with a force pump for positively propelling the oil, of an oil tank, an oil delivery conduit connecting said tank with the suction of said pump, a hydrostatic feed for delivering the oil into said conduit, and means for also introducing a fluid medium therein and a sight feed in said oil delivery conduit.

6. In a lubricator, the combination with a fluid operated force pump for positively

propelling the oil, of a tallow pipe into which the oil is delivered, a check valve controlling the oil discharge into said tallow pipe, and means for maintaining a resistance 5 to the opening of said valve which is proportional to the pressure actuating said pump and is in excess of the maximum back pressure developed in said tallow pipe.

7. In a lubricator, the combination with a 10 force pump for positively propelling the oil, of a tallow pipe into which the oil is delivered from said pump, a check valve controlling the discharge from said pump into said tallow pipe, said valve being provided 15 with an enlarged head, a cylinder in which said head is slidingly secured, and a steam connection between said cylinder and the boiler whereby said head is subjected to a pressure in excess of the maximum back 20 pressure developed in said tallow pipe and operating upon said valve.

8. In a lubricator, the combination with 25 an oil tank, of a hydrostatic sight feed for delivering the oil therefrom, and the fitting J forming the discharge connection from said sight feed, said fitting having the threaded nipple d adapted to engage the correspondingly threaded aperture in the tank, the radiator L extending from said nipple into 30 the tank, a steam inlet connection to said

fitting, the valve N controlling said steam inlet connection to said fitting, said fitting having the passage f therein for connecting said steam inlet connection with said radiator, and having the restricted port h for 35 delivering the condensation into the sight feed.

9. In a lubricator, the combination with an oil tank, of a hydrostatic sight feed for delivering the oil from said tank, a force 40 pump for positively propelling the oil delivered from said sight feed, a conduit connecting said sight feed with the suction of said pump, a check valve in said conduit, a steam connection to said check valve for 45 counterbalancing the steam pressure operating through said hydrostatic feed, and a restricted port from said steam connection to said conduit whereby fluid medium is introduced into said conduit for conveying the 50 oil to said pump and condensation is furnished for replenishing the water of the sight feed.

In testimony whereof I affix my signature in presence of two witnesses.

ELIJAH McCOY.
